UNITED STATES PATENT OFFICE.

MONVILLE HOLMDAHL, OF VALLEJO, CALIFORNIA.

DESIGN FOR A SIGNAL PANEL FOR AUTOMOTIVE VEHICLE SIGNAL DEVICE.

Application filed January 17, 1928. Serial No. 24,907. Term of patent 14 years.

To all whom it may concern:

Be it known that I, MONVILLE HOLMDAHL, a citizen of the United States, residing at Vallejo, county of Solano, State of California, have invented a new, original, and ornamental Design for Signal Panel for Automotive Vehicle Signal Device, of which the following is a specification, reference being had to the accompanying drawings, forming part thereof.

Figure 1 is a view in front elevation of a signal panel for automotive vehicle signal device showing my new design.

Figure 2 is an end elevation of the signal panel disclosed in Fig. 1.

I claim:

The ornamental design for signal panel for automotive vehicle signal device, as shown.

MONVILLE HOLMDAHL.
